UNITED STATES PATENT OFFICE

WALTER O. GORR, OF NEW YORK, N. Y., ASSIGNOR TO ROBERT C. DUNBAR, CLEMENT B. HARTS, AND EDNA K. FERRISS, OF NEW YORK, N. Y.

STENCIL HAND STAMP

Application filed April 8, 1929. Serial No. 353,574.

The present invention relates to improvements in the form of stencil hand stamps or duplicators such as covered by an application filed by me October 20, 1928, Serial No. 5 313,814, in which a hollow stamp body is formed with a foraminous bottom wall over which are stretched the inking pad stencil sheet.

The present improvements relate first to 10 the provision of said hollow stamp body with an internal partition dividing the hollow body into separate chambers for the reception of different colored inks. The divided chambers are preferably in free communication 15 with an opening in the top wall, through which opening inks may be inserted or spread upon the inner surface of the foraminous bottom wall.

The second feature of the present invention 20 comprises a detachable sheet gaging guide which is readily mounted upon the stamp body adjacent to one edge of the foraminous bottom wall so as to afford ready means for gaging the operation of the hand stamp upon 25 successive sheets of paper. Preferably this detachable guide plate is formed with a longitudinal angular flange having keyhole openings or perforations designed to engage the headed pins or lugs at one side of the 30 foraminous bottom wall, said pins or lugs being part of the means for securing the inking pad and the stencil sheet to the hand stamp.

The third feature of the present invention 35 comprises an improved form of protecting tray to fit over and support the hand stamp when it is not in use. This tray, which may be open-ended, is formed with longitudinal channels adjacent to the upper edges of its 40 side walls, said channels affording rectangular flanges or shoulders upon which rest the oppositely projecting pins or lugs of the hand stamp. The upper edges of the tray side walls are also bent to form flanges or ledges 45 for the engagement of said pins or lugs to support the hand stamp. When the hand stamp is in engagement with the channels of the tray the springy nature of the side walls will hold such engagement so that the tray 50 will hold its engagement and be moved with

the hand stamp. The other or top supporting flanges of the tray side walls is for temporary support of the hand stamp where its operation is only temporarily interrupted.

In order that the invention may be more 55 fully understood it will first be described with reference to the accompanying drawings and afterwards more particularly pointed out in the annexed claims.

In said drawings:

Figure 1 is a longitudinal vertical sectional view of a hand stamp showing a central transverse partition to divide the internal chamber of the stamp body into two separate ink receiving chambers;

Figure 2 is a vertical transverse sectional view of the same;

Figure 3 is a detail transverse vertical sectional view illustrating a modified form of partition wall;

Figure 4 is a horizontal sectional view taken on the line 4-4 of Figure 3;

Figure 5 is a top perspective view particularly illustrating the removable sheet gaging guide plate;

Figure 6 is an end elevation of the same illustrating the sheet gaging operation;

Figure 7 is a perspective view of the detached sheet gaging guide plate;

Figure 8 is a vertical transverse sectional view illustrating the improved protecting tray with the hand stamp resting therein; and

Figure 9 is a perspective view of the protecting tray alone.

The hollow body of the improved stencil hand stamp is formed of a top plate 1 having the integral downwardly presented side flanges 2 extending at right angles to the top plate and to which the opposite edges of the segmental cylindrical bottom wall 3 are brazed or soldered. The bottom wall 3 is closely perforated throughout the greater part of its area. The hollow body is completed by the two end wall sections 4 which are brazed or soldered to the flanged top plate 1 and the foraminous bottom wall 3.

The top wall 1 has a relatively large central rectangular opening 5 cut through it, in which closely fits a removable cover plate 6 100

resting preferably upon a flange or stop plate 7 secured to the inner surface of the top plate 1 and projecting slightly within the cover opening 5 to provide a ledge for the support of the cover plate 6. The cover plate 6 has 5 rotatably mounted upon it a handle 8 secured by means of a bolt or screw 9 inserted from beneath and passing through a locking bar 10 which is keyed or otherwise fastened to 10 the bolt or screw 9 so as to rotate upon the cover plate 6 with the handle 8. Spacing washers 11 and 12 are mounted between the locking bar 10 and cover plate and between the handle 8 and cover plate for the purpose of giving the handle and locking bar more 15 freedom of movement.

15 is the ink pad and 20 is the stencil, these elements being of any preferred form, but preferably constructed as described in my 20 above named application, Serial No. 313,814.

The first feature of improvement of the present invention consists in providing a partition wall such as indicated at 50 in Figures 1 and 2 or at 55 in Figures 3 and 4. The 25 partition in the hollow chamber of the hand stamp body is for the purpose of forming separate chambers for different colored inks. In the form shown in Figures 1 and 2 there are two distinct chambers divided in the middle of the hand stamp, both in free communication with the top ink opening 5 through which ink may be poured or spread with a brush upon the inner surface of the divided curved rounded bottom wall. In the form 30 shown in Figures 3 and 4 of the drawings the partition 55 is of oval shape forming a central oval chamber and a main chamber entirely surrounding the same.

To rapidly print upon a succession of sheets 40 of paper it is desirable to have a gaging guide plate with which the edge of the sheet may be brought in engagement to indicate the printing position of the stencil with reference to the sheet. Such a guide plate is provided in the present case in the form of a detachable plate indicated at 60 and having a rectangular longitudinal flange 61 formed with 45 perforations or openings of keyhole shape 62 which are adapted to fit over the headed pins or lugs 30 with which one edge of the inking pad and stencil sheet are engaged. The large portion of the opening 62 is slipped over the headed pins 30 and the guide plate 60 then moved longitudinally upon the pins until the 50 heads engage the narrow parts of the opening and securely hold the guide plate in position. The operation of gaging the position of the hand stamp with reference to the sheet indicated at S is clearly indicated in Figure 6 of 55 the drawings.

Returning to consideration of the body of the stencil hand stamp, it will be observed that one of the longitudinal side walls 2 is provided with outwardly projecting headed pins or lugs 30, four of them being employed

on a large size stamp. These headed pins or lugs 30 are spaced to correspond with the spacing between the perforations or openings 18 of the pad 15 and 25 of the stencil 20 so that one edge of the pad and one edge of the stencil can be mounted upon these headed pins or lugs, the stencil being superposed upon the pad.

At the opposite side of the stencil body, the top plate 1 has projecting up from it two headed guide pins 35 over which fit the perforations 36 of the angular tension bar 37. Projecting from the side of the angle bar 37 are the four spaced headed pins or lugs 38 corresponding in position and spacing to the pins or lugs 30 above referred to.

In Figures 8 and 9 is shown a protecting tray 75 for the reception of the hand stamp. This tray is formed with upwardly presented springy side walls 76 formed near their upper 85 edges with longitudinal channels 77 providing horizontal flanges or ledges 78 and with their extreme upper edges shaped into horizontal flanges 79. The flanges or ledges 78 and 79 are approximately at right angles to the side walls 76 of the tray.

When the stamp is out of use it is placed in the position indicated in full lines in Figure 8 of the drawings in which the headed pins 30 and 38 rest in the channels 77 upon the ledges 78, the spring of the side walls holding them inwardly in yielding engagement with said pins so that the hand stamp when picked up will carry the protecting tray with it. When the hand stamp is being used with but short intervals of interruption, it is placed in position upon the tray 75 as indicated in dotted lines in Figure 8, in which position the pins 30 and 38 rest upon the top longitudinal flanges 79 and permit the hand stamp to be picked up and separated from the tray.

I claim:

1. A stencil hand stamp comprising a hollow body having a foraminous bottom wall, an internal partition wall intersecting parts of said foraminous bottom wall and dividing said hollow body into separate chambers for different colored inks, and an ink pad and a stencil sheet extending over said foraminous bottom wall, and acting in common for different colored inks in said separate chambers.

2. A stencil hand stamp comprising a hollow body having a foraminous segmental cylindrical bottom wall, an internal partition wall intersecting parts of said bottom wall and dividing said hollow body into separate chambers for different colored inks, and an ink pad and a stencil sheet mounted upon said hollow body over said foraminous bottom wall and acting in common for different colored inks in said separate chambers.

3. A stencil hand stamp comprising a hollow body having a foraminous bottom wall, a top wall with covered opening, and an in-

ternal partition wall dividing said hollow body into separate chambers for different colored inks, said separate chambers being in communication with the top wall opening.

4. A stencil hand stamp comprising a hollow body having a foraminous bottom wall and imperforate top, side and end walls, said top wall being formed with a covered inking opening, and an internal partition wall dividing said hollow body into separate chambers for different colored inks, said separate chambers being in communication with the top wall opening.

5. A stencil hand stamp comprising a hollow body having a foraminous bottom wall, a top wall with covered opening, an internal partition wall traversing said top wall opening and dividing said hollow body into separate chambers for different colored inks, said separate chambers being in communication with the top wall opening, and an operating handle.

6. A stencil hand stamp comprising a hollow body having a foraminous bottom wall, a top wall with inking opening, a cover plate for said opening, a handle attached to said cover plate, an internal partition wall dividing said hollow body into separate chambers for different colored inks, said separate chambers being in communication with said top wall opening, and an ink pad and stencil sheet extending over said foraminous bottom wall.

7. A stencil hand stamp comprising a hollow body having a foraminous bottom wall, pins or lugs projecting from said body adjacent one edge of said foraminous bottom wall, a sheet gaging printing guide plate having means for detachably mounting it upon said pins or lugs.

8. A stencil hand stamp comprising a hollow body having a foraminous curved bottom wall, headed pins or lugs projecting from said body adjacent one edge of said foraminous bottom wall, an ink pad and a stencil sheet extending over said bottom wall, a printing guide plate having perforations to fit over said headed pins or lugs for detachably mounting said plate.

9. A combination with a stencil hand stamp having outwardly projecting pins or lugs to engage the removable ink pad and stencil sheet, with a protecting tray having upright side walls formed adjacent to their upper edges with longitudinal shoulders to receive the projections upon the hand stamp.

10. A combination with a stencil hand stamp having outwardly projecting pins or lugs to engage the removable ink pad and stencil sheet, with a protecting tray having upright springy side walls formed adjacent to their upper edges with longitudinal shouldered channels to receive the projecting pins or lugs upon the hand stamp.

11. The combination with a stencil hand

stamp carrying an inking pad and stencil, with a protecting tray having upwardly presented springy side walls formed with longitudinal channels adjacent to their upper edges and flanged top edges for the engagement and support of the hand stamp.
